Patented May 9, 1967

207,579

FRAME FOR A GOLF CART

William D. Jones, E. Club Drive,
Thomasville, Ga. 31792

Filed Sept. 23, 1965, Ser. No. 87,132

Term of patent 3½ years

(Cl. D14—3)

Fig. 1.

Fig. 2.

Fig. 3.

Fig. 4.

Fig. 5.

FIGURE 1 is a front perspective view of a frame for a golf cart showing my design,

FIGURE 2 is a side elevation thereof,

FIGURE 3 is a top plan view thereof,

FIGURE 4 is a rear elevational view thereof, and

FIGURE 5 is a front elevational view thereof.

The broken lines in the drawings are for illustrative purposes only.

I claim:

The ornamental design for a frame for a golf cart, as shown and described.
